UNITED STATES PATENT OFFICE.

GEORGE W. C. WOOLERY, OF BEDFORD, INDIANA.

SASH-FASTENER.

SPECIFICATION forming part of Letters Patent No. 582,935, dated January 22, 1895.

Application filed June 1, 1894. Serial No. 513,172. (No model.)

To all whom it may concern:

Be it known that I, GEORGE W. C. WOOLERY, of Bedford, in the county of Lawrence and State of Indiana, have invented a new and useful Improved Sash Lock and Support, of which the following is a full, clear, and exact description.

The object of the invention is to provide means for adjusting the tension of the spring of the locking bolt.

To these ends my invention consists in the construction and combination of parts, as is hereinafter described and indicated in the claim.

Reference is to be had to the accompanying drawings, forming a part of this specification, in which similar figures of reference indicate corresponding parts in all the views shown.

Figure 1 is an inner side view of a window in part, showing the casement in section, and the novel sash locking device in locked adjustment on the lower sash. Fig. 2 is a detached sectional plan view of a portion of the improvement, on the line 2—2 in Fig. 4, it being a spring supporting device for one side of a sash. Fig. 3 is a sectional side view of the part of the improvement shown in Fig. 2, on the line 3—3 in Fig. 4. Fig. 4 is a transverse sectional view of parts of the sash counter-balancing features of the improvement, taken on the line 4—4 in Fig. 3. Fig. 5 is a transverse sectional view of a portion of the lower sash and casement, and a sectional plan view of the sash-locking portion of the improvement, on the sash and casement, taken on the line 5—5 in Figs. 1 and 6. Fig. 6 is a sectional side view of the portion of the sash-locking device, on the line 6—6 in Fig. 5, having parts slightly changed in adjustment from that shown in Fig. 5. Fig. 7 is a detached side view of one of a series of locking disks that are in certain cases used in connection with the other improvements that have been indicated; and Fig. 8 is a side view of the preferred device for use as a sash support, and detent for the locking device, and that in service is embedded in the stiles of the window casement, the part shown in Fig. 7 being a modified form of this part of the improvement.

Referring to the drawings, 10 represents the casement portion of a window in part, whereon the improvement is shown, and 11 the pre-

ferred detent device which is embedded in the faces of the casement stiles and there secured by screws or by other means. As indicated 55 in the views where they appear, the similar detent plates 11, each consist of an elongated sheet metal or other thin metallic strip having the bottom curved cavities 11^a, formed in it from the side that is nearest to the vertical 60 edge of the sash when the latter is in position for service, said cavities being properly spaced apart at opposite points on the pair of strips furnished for each sash of a window, these parts being clearly represented in Figs. 1 and 65 8 of the drawings.

The sash lock proper comprises an elongated thin metal case 12, that may be oval in cross section, as is indicated in Fig. 4 for the similar case provided for the sash support at the opposite side of the window. The case 12 is for convenience formed in two half sections that are joined together by any available means, one method for locking them together consisting in the perforation of the case sections oppositely at a proper point between the ends of the same, and introducing a transverse wall 12^a having projecting ears that pass through the perforations mentioned, and are then bent over on the exterior of the case, thereby 70 clamping the latter on the transverse wall, as indicated in Figs. 2, 4 and 5. There is an end wall 12^b formed on the case sections, which wall is centrally perforated for the reception of one end of the cylindrical slide bolt 75 13, that is similarly projected through a center hole in the cross wall 12^a toward the opposite end of the case. A collar 13^a is formed on the bolt 13, at a correct distance from the end that loosely engages the perforated end 80 wall 12^b, and serves to limit the outward sliding movement of this end portion of the bolt. A coiled spring 14, of proper strength for effective service, is placed on the body of the bolt 13, and when the parts of the sash lock 85 are assembled, this spring has an enforced contact at its ends on the collar 13^a, and transverse wall 12^a, so that the bolt is normally projected from the case, as shown in Figs. 5 and 6.

A peripherally circular block 15, is provided with eccentrically and oppositely located journal studs 15^a, that loosely engage opposite site perforations in the sides of the case 12.

at proper points behind the inner end of the slide bolt 13, so that when the cam block 15, is disposed as shown in Fig. 5, the bolt named will be permitted to move rearwardly, and if the swell on said cam block is forwardly adjusted, as represented in Fig. 6, the slide block will be locked in a projected condition. For the convenient manipulation of the cam block 15, a notched indentation is produced in the end of one of its journal studs 15^a, to receive the end of a key 15^b, as represented in Fig. 5, so that the application of the key and its partial rotation will adjust the cam block as required, either to lock or release the bolt 13.

The portion of the device that is provided to aid in sustaining the sash, which has been already mentioned, consists of a case 16, that is formed substantially like the case 12, and of similar dimensions, a slide bolt 13 being located within said case 16 and is the duplicate of the slide bolt in the sash locking portion of the improvement.

As represented in Figs. 2 and 3, the bolt in the case 16, is supported to slide endwise therein by the loose engagement of one of its ends with a central perforation in the end wall of the case, its inner end portion being adapted to slide through a center hole in the transverse wall 16^a, that in a like manner as the transverse wall 12^a of the case 12, is provided with locking ears 16^b.

In order to permit an increase in the tensional force of the spring 17, that is located on the slide bolt 13 in the case 16, spaced slots are oppositely formed in the case, as shown at 16^c in Figs. 2 and 3, which the ears 16^b may be located in, it being evident that the location of the wall 16^a nearer the outer end of the case 16, will proportionally compress the spring 17 and increase its resistance to further compression.

To place the complete improvement on a window for its support and secure locking when this is desired, there are opposite recesses or socket holes formed in the side edges of the sash, such as 10^a, of a suitable size to receive the cases 12 and 16 of the sash-supporting and locking devices, which should closely fit in these holes.

To facilitate the use of the key 15^b, there should be a slot of proper size cut in the side rail of the window sash at a point that will expose the notched end of the stud on the cam block of the sash lock, as shown in Fig. 5, which slot and stud should be located on the inner side of the window, an escutcheon plate 15^c being secured over the key slot to form a neat finish for the same.

As before explained, the detent plates 11 are located at opposite points in the stiles of the window casement, they being embedded so as

not to obstruct the free sliding movement of the sash, and for the correct operation of the sash supporting and locking devices, the cases that contain the working parts of the same should be introduced within the side bars of the sash at such points as will permit the outer ends of the slide bolts 13 to enter the curve-bottomed recesses or cavities in the detent plates, when the upper and lower sashes are in a closed condition.

It will be seen that if the springs which press the bolts 13 are of sufficient strength, the weight of the sash will be sustained by the projected ends of these bolts, that are forced by spring pressure into the cavities of the detent plates that lie opposite said bolts.

To permit a free reciprocation of the sash, the outer ends of the bolts 13 should be slightly rounded, so that the application of moderate force to the sashes of the window will enable them to be slid and located at different points of open adjustment, or to completely close them, and it is evident that by a manipulation of the key 15^b, the slide bolt of the sash lock may be secured so as to prevent it from retracting, and thus lock the window sash either open or closed.

In Fig. 7, there is a recessed locking disk 18 shown, which is designed in some cases to take the place of the detent plates 11, as these disks are more easily inserted in window casements that are in use in houses. Such disks are then of service to permit the convenient application of the improvements to old houses, they being located in the stiles of the window casement at proper intervals for a locking engagement with the slide bolts of the sash supporting and locking devices.

Having thus described my invention, I claim as new and desire to secure by Letters Patent—

The herein described sash holder and fastener consisting in the longitudinally divided tubular case having a series of apertures 16^c in its two sections, a partition 16^a having a central aperture and end tongues 16^b passed through any aligned pair of said apertures and bent over at right angles to hold the sections together, a spring projected bolt guided in and having its tension adjusted by said partition and having a rounded nose, a cam to engage the rear end of the bolt and lock it projected, said cam having trunnions mounted in apertures in the said sections, and a series of rounding sockets for the nose of the bolt to enter and act as a friction holder or a positive fastener, substantially as described.

GEORGE W. C. WOOLERY.
